(57) **CLAIM**

The ornamental design for a bite-actuated mouthpiece, as shown and described.

DESCRIPTION

FIG. 1 is a perspective view of a bite-actuated mouthpiece showing our new design;

FIG. 2 is a front view thereof;

FIG. 3 is a rear view thereof;

FIG. 4 is side view thereof;

FIG. 5 is another side view thereof;

FIG. 6 is a top view thereof;

FIG. 7 is a bottom view thereof;

FIG. 8 is another perspective view thereof;

FIG. 9 is another perspective view thereof; and,

FIG. 10 is another perspective view thereof.

The dashed lines shown in the drawings illustrate portions of the bite-actuated mouthpiece that are not presently claimed and thus form no part of the presently claimed design. The shading lines shown in the drawings represent the three-dimensional contour of the claimed design and are not intended to indicate surface decoration.
